UNITED STATES PATENT OFFICE.

THOMAS GERHARD LUSON, OF BLACKHEATH, LONDON, ENGLAND.

SET-SCREW FOR LAMP GLOBES AND SHADES.

No. 808,290.

Specification of Letters Patent.

Patented Dec. 26, 1905.

Application filed March 28, 1905. Serial No. 252,567.

To all whom it may concern:

Be it known that I, THOMAS GERHARD LUSON, clerk, a subject of the King of Great Britain, and a resident of 1 Old Dover road, 5 Blackheath, London, England, have invented a new and useful Improvement in Set-Screws for Lamp Globes and Shades, of which the following is a specification.

Globes and shades for gas and other lamps are frequently secured in position on their galleries or supports by means of set-screws. These screws grip the edge or lip of the globe or shade more or less tightly. The globe being of glass is subject to considerable expansion and contraction by reason of the variation in temperature caused by the lighting or extinguishing of the lamp. The set-screws, however, as at present used are not equally responsive to variations in 10 temperature, and there is nothing to prevent them from being screwed too tight. Consequently, therefore, there is constant danger of undue pressure from the screws, which pressure is liable to cause the fracture 15 of the globe.

According to my invention I provide set-screws so constructed that they cannot grip too tightly, but will press only elastically on the globe or shade and will yield to the 20 glass in expansion or contraction as and when required.

In the accompanying drawings I have shown a set-screw constructed according to my invention.

35 Figure 1 is a longitudinal section through the screw, which is shown much larger than the size which will usually be employed. Fig. 2 shows it in position securing a gas-globe to a gallery. Fig. 3 is a view similar 40 to Fig. 1, showing the screw slightly differently made.

The screw comprises a hollow body *a*, externally threaded at one end to screw into the gallery or support. Internally the body 45 *a* is of two diameters *b* and *c*, *b* being the larger. Within the body *a* is a plunger *d*, having a collar *e*, which fits easily the larger end *b* and is capable of sliding therein. The plunger fits easily the narrower portion 50 of the hollow screw-body, and its end, preferably rounded off, protrudes beyond the body *a* in the manner shown. At the back the hollow body *a* is closed by a screw-cap *f*, which may either be annular to permit 55 the passage of the back end of the plunger

d (see Fig. 1) or solid, as shown in Fig. 3. Between the cap and the collar *e* of the plunger is interposed a spring *g*. This spring *g* gives to the plunger *d* an elastic tendency outward, so that when in position to secure 60 a globe, as shown at Fig. 2, it is capable of yielding. In this manner the globe is held by an elastic grip, and hence the tendency to fracture the globe above referred to is removed.

65 *h* is a shoulder on the screw, so placed as to prevent overscrewing, which might neutralize the advantages of the spring-seated plunger. When, however, the form of screw shown in Figs. 1 and 2 is used, any tendency 70 to bind the glass too tightly will be detected by the operator opening the back end of the plunger protruding through the hole in the cap *f*.

75 What I claim as my invention, and desire to secure by Letters Patent, is—

1. A removable set-screw for use in supporting a lamp globe or shade from a gallery, comprising a hollow body having a screw-threaded engagement with the gallery, a 80 plunger sliding in the hollow body, a collar on the plunger, a cap screwed into the end of the hollow body and a spring interposed between the collar and cap, as and for the purpose set forth.

85 2. A removable set-screw for use in supporting a lamp globe or shade from a gallery, comprising a hollow body having an external thread thereon for engagement with the gallery, an exterior shoulder on the hollow body for preventing overscrewing of the same, a plunger sliding within the hollow body and a spring arranged to yieldingly force the plunger outwardly as and for the purpose set forth.

90 3. A removable set-screw for use in supporting a lamp globe or shade from a gallery, comprising a hollow body having a screw-threaded engagement with the gallery and a spring-actuated plunger sliding in the hollow 100 body and arranged to protrude at either end thereof, substantially as and for the purpose set forth.

95 In testimony whereof I have signed my name to this specification in the presence of 105 two subscribing witnesses.

THOMAS GERHARD LUSON.
